ELECTRIC FILTER

Theodorus Josephus Weyers, Eindhoven, Netherlands, assignor, by mesne assignments, to Hartford National Bank and Trust Company, Hartford, Conn., as trustee

Application February 10, 1938, Serial No. 189,854
In Germany February 18, 1937

1 Claim. (Cl. 178—44)

My invention relates to electric filters.

In designing electric filters one frequently starts from the ideal case in which a filter is terminated at its input and output terminals by image impedance and comprises coils and condensers which cause no losses. Such an ideal filter has two cut-off frequencies f_1 and f_2 , both of which have finite values in the case of a band-pass filter, and one of which has an infinite or zero value in the case of a high-pass or low-pass filter. Such an ideal filter has no attenuation in the pass-band, e. g. in the region between the two cut off frequencies, but frequencies lying outside this frequency band are attenuated. However, in practice the attenuation in the pass-band is not constant but varies to a large extent with the frequency because the condensers and coils have losses and the filter is not terminated by image impedances.

The object of my invention is to overcome the above difficulties and to provide a filter whose attenuation curve is substantially flat in the pass-band.

According to the invention I connect in series and/or in parallel with a terminal impedance and/or between two filter sections, a resonance circuit tuned to a frequency lying in the pass-band and comprising an ohmic resistance, the inductance and capacity of the resonance circuit and the resistance being so selected that the attenuation in the pass-band is substantially constant.

In order that the invention may be more clearly understood and readily carried into effect, I shall describe the same in more detail with reference to the accompanying drawing in which:

Figure 1 is a graph for use in explaining the invention; and

Figs. 2 and 3 are schematic diagrams of filters according to the invention.

In the graph of Fig. 1 the frequency (f) and the attenuation (α) are plotted as abscissae and the ordinates respectively, and reference letter a indicates the damping curve of an ideal band-pass filter. The cut off frequencies of the pass-band are denoted by f_1 and f_2 .

However, as stated above, the coils and condensers of an actual filter have losses, and in practice the condition that the filter should be terminated by impedances which are, for all the frequencies, equal to the image impedances which depend on frequency is seldom fulfilled. The terminal impedances generally are, for example, ohmic resistances which are so selected that, for the mean frequency

$$f_m = \sqrt{f_1 f_2}$$

of the transmitted frequencies, the terminal resistances are equal to the image impedances. Due to the losses and to the mismatching, the

attenuation curve of such a practical filter differs from curve a , and has, for example, a shape similar to the dotted curve indicated by reference letter b . As appears from Fig. 1, the attenuation of curve b in the pass-band is not constant but varies to an appreciable amount with the frequency. This phenomenon is very undesirable and is eliminated or at least greatly diminished by the present invention.

Fig. 2 schematically illustrates a filter F to which is connected an output impedance Z_b . In accordance with the invention, a series resonance circuit comprising an inductance coil L , a condenser C , and a resistance R is connected across the output impedance. If L and C are given such values that series-resonance occurs at the mean frequency f_m of the transmitted frequencies, the circuit LCR behaves for this frequency as if only the resistance R were present. As resistance R is connected in parallel with the output impedance Z_b , it therefore increases the attenuation of the filter, and by giving it a proper value it is possible to give the attenuation for the mean frequency f_m a value (see Fig. 1) substantially equal to or preferably slightly larger than the attenuation of the filter at the cut off frequencies f_1 and f_2 without the resonance circuit. Although for frequencies higher or lower than the mean frequency to which L and C are tuned, the impedance of circuit LCR increases and brings about attenuation, this is less than for the mean frequency f_m . In fact, as appears from Fig. 1, circuit LCR has only a slight influence at the cut off frequencies f_1 and f_2 , and at these points brings about substantially the same attenuation as in the absence of the circuit. Thus an attenuation curve having a substantially flat shape in the pass-band can be obtained by giving the attenuation for the mean frequency a value which is substantially equal to that of the attenuation for the cut off frequencies.

The circuit arrangement schematically illustrated in Figure 3 is the same as that of Fig. 2, except that a parallel resonance circuit LCR is connected in series with the terminal impedance Z_b , instead of a series resonance circuit connected in parallel with the terminal impedance as shown in Figure 2. Such a circuit-arrangement gives the same results as that of Fig. 2. It is also possible to connect the series resonance circuit of Fig. 2 or the parallel resonance circuit of Fig. 2 between two filter sections or into the input circuit of the filter.

In the above it was assumed that the filters had, before the application of the resonance circuit, a symmetrical attenuation curve so that the resonance circuit was tuned to the mean frequency. In those cases in which the attenuation curve is unsymmetrical with respect to the mean frequency, it is, however, more advantageous to

- tune the resonance circuit to a frequency which differs from the mean frequency, for example to that frequency in the pass-band for which the attenuation is smallest.
- 5 The invention may also be applied to high-pass and low-pass filters which can be considered as special types of band-pass filters in which $f_m=f_2=\infty$ and $f_m=f_1=0$ respectively, and also to band-eliminating filters.
- 10 While I have described my invention in connection with specific examples and applications, I do not wish to be limited thereto, but desire the appended claim to be construed as broadly as permissible in view of the prior art.
- 15 What I claim is:

A circuit arrangement comprising an electric

filter, an impedance connected to the terminals of said filter, and means for producing a substantially constant attenuation in the pass-band of the filter comprising a resonance circuit tuned to a frequency lying within the pass-band of the filter and having an ohmic resistance, an inductance, and a capacity, said resistance, inductance and capacity being connected in parallel with each other and in series with said impedance, said ohmic resistance having a value at 10 which the attenuation at the frequency to which the resonance circuit is tuned is substantially equal to the attenuation at the cut-off frequency or frequencies.
